UNITED STATES PATENT OFFICE

139,032

DESIGN FOR A HIGHWAY SIGNAL

Timothy D. Wandell, Steamboat Springs, Colo.

Application June 28, 1944, Serial No. 114,242

Term of patent 3½ years

(Cl. D72—1)

To all whom it may concern:

Be it known that I, Timothy D. Wandell, a citizen of the United States, residing at Steamboat Springs, in the county of Routt and State of Colorado, have invented a new, original, and ornamental Design for a Highway Signal, of which the following is a specification, reference being had to the accompanying drawing, forming part thereof.

Figure 1 is a front elevational view of a highway signal showing my new design.

Figure 2 is a side elevational view, and
Figure 3 is a rear elevational view thereof.

I claim:
The ornamental design for a highway signal,
as shown.

TIMOTHY D. WANDELL.
